UNITED STATES PATENT OFFICE

2,383,651

BOOT HOLDER

Harvey W. Hill, Parkville, Mo.

Application September 11, 1943, Serial No. 502,045

15 Claims. (Cl. 12—129.1)

This invention relates to a boot holder or the like, and more particularly to a holder adapted for supporting such articles while being dried.

When drying boots, waders and shoes, and particularly what is called "hip boots" commonly used by hunters and fishermen, it is desirable to hold the articles in approximately the shape and form as when they are in use, which provides for better circulation of air and rapid and even drying.

Further objects of the invention are to provide an improved holder of the character referred to which is adapted to support a boot or the like in position more conducive to rapid, uniform drying; to provide a device which will hold the sole of the shoe or boot in a flat position so as to prevent the toe from curling upwardly; to provide a device which can be instantly adjusted to fit any size of boot; to provide a device which may be folded and packed in a container in flat position, and to provide a device easily and inexpensively to manufacture.

In accomplishing these and other objects of the invention, as hereinafter pointed out, I have provided improved details of structure, the preferred form of which is illustrated in the accompanying drawing, wherein:

Fig. 1 is a perspective view of a boot holder embodying the features of the present invention applied to a boot.

Fig. 2 is an elevational view of the device when viewed from the toe end thereof.

Fig. 3 is a top plan view of the device embodying my invention.

Referring more in detail to the drawing:

1 designates a boot holder consisting of a body portion 2 made from a single piece of wire or rod, having a straight portion 3 of at least half the length of the boot to be supported, the wire then being bent outwardly as at 4 to form a sole portion of the holder extending approximately to the toe 5 of the boot. The portion 4 is bent downwardly, inwardly and upwardly as at 6 to form a loop portion 7 adapted to engage under the toe 5 of said boot, the end of the loop portion 7 being bent inwardly and rearwardly as at 8 to form a second sole portion 9 extending to the bend 3 in the body portion 2, where the sole portion 9 is bent over the rod 2 to form a coil 10 holding the portions 4 and 9 in the shape of a V, the end of the coil 10 being provided with a loop 11 extending upwardly from the rod 2 to form a hanger support, as later described.

The bars 4 and 9 form a rigid support for the sole 12 of the boot 13 when the loop portion 7 is engaged over the toe 5 of the boot.

The body portion 2 extends rearwardly of the coil 10 past the heel portion 14 of the boot, and is provided with a stop member 15 that is rigidly attached to the rear end of the body portion 2, as by welding. The rear end of the body portion 2 is also screw threaded as at 16 and carries a nut 17 to adjust the position of a heel engaging member 18 on the body member 2 to accommodate the device for the particular size of boot to be supported.

The heel engaging member comprises a U-shaped strap member 19 having spaced arms 20 and 21 connected at their upper edges by a bar portion 22. The arms 20 and 21 have apertures 23 and 24, respectively, through which the body member 2 projects to slidably mount the member 18 thereon.

The side 21 of the U-shaped member 19 is provided with a forwardly turned flange 25, the forward edge 26 of which is adapted to engage the point of connection of the heel and the boot to which the device is to be attached.

A coil spring 27 is sleeved on the body portion 2 between the nut 17 and the arm 20 of the heel engaging member 18 to exert suitable pressure against the arm member to hold the heel engaging member 18 in engagement with the heel of the boot, the pressure of the spring 27 being sufficient that the engagement of the heel engaging member with the heel of the boot will hold the toe portion 5 thereof in the loop 7, whereby the weight of the boot may be carried by said heel engaging member and the loop 7.

The arm 20 of the U-shaped member 19 extends downwardly below the flange 25 to provide a hand hold for exerting pressure against the coil spring to open the device so that it may be placed on a boot or to disengage the member 18 from engagement with the heel of a boot after it has been applied thereto.

In order to provide for hanging the boot holder and boot in a suitable place of storage or for drying, I provide a hook member 28 having an eye portion 29 at the lower end thereof adapted to be secured to the loop 11, said loop 11 and eye 29 being sufficiently large to permit free movement of the hook member 28 relative to the body portion 2 of the boot holder. The upper end of the hook member is provided with a hook 30 of suitable shape to engage over a rod or other hanging device (not shown).

The operation of a device constructed as described is as follows:

After adjustment of the nut 17 on the screw threaded portion 16 of the rod 2 for the size of boot to be hung, the loop 7 of the device is hooked

under the toe of a boot to be dried and by placing the thumb of the operator of the device on the stop member 15 and applying force on the downwardly extending arm portion 20 of the heel engaging member 18 by the forefinger of the hand of the operator pressure will be exerted against the coil spring 27 to open the device so that the arm portion 21 of the heel engaging member 18 may engage the heel of the boot to be dried. The boot is then hung by the hook 28 in a convenient place for drying.

Holders embodying my invention preferably are adjustable to accommodate boots of different sizes within wide ranges.

A holder constructed in accordance with my invention is of light, simple and inexpensive construction which may be readily adjusted, assembled and disassembled for packing or carrying in a car, grip, duffle bag or the like.

What I claim and desire to secure by Letters Patent is:

1. In a device of the character described, a body member having a portion at one end thereof for engaging the toe of a boot, means for engaging the heel of said boot, said heel engaging means being adjustable on the body member to adapt the device to fit different size boots, and means hingedly connected at substantially the center of the body member for supporting same and the boot to which it is applied.

2. In a device of the character described, a body member having a portion at one end thereof for engaging the toe of a boot, a U-shaped member for engaging the heel of said boot, said U-shaped member being movable on the body member to adapt the device to fit different size boots, means for adjusting the tension on the U-shaped member, and means engaging the body member at substantially the center thereof for supporting same and the boot to which it is applied.

3. In a device of the character described, a body member having a portion at one end thereof for engaging the toe of a boot, a member for engaging the heel of said boot, said heel engaging member being adjustable on the body member to adapt the device to fit different size boots, and means hingedly connected at substantially the center of the body member for hanging the device after the device is applied to a boot.

4. A boot holder comprising a wire rod formed in the shape of a triangle, the base of which is shaped downwardly and inwardly to form a loop for engaging the toe of a boot, a body member extending rearwardly of the boot from the apex of the triangle, means on the body member for engaging the heel of the boot to cooperate with loop member in supporting the boot, and means for hanging the device after the device is applied to a boot.

5. A boot holder comprising a wire rod formed in the shape of a triangle, the base of which is shaped downwardly and inwardly to form a loop for engaging the toe of a boot, a body member extending rearwardly of the boot from the apex of the triangle, and means movable on the extension for engaging the heel of the boot to cooperate with the loop member in supporting the boot.

6. A boot holder comprising a wire rod formed in the shape of a triangle, the base of which is shaped downwardly and inwardly to form a loop for engaging the toe of a boot, a body member extending rearwardly of the boot from the apex of the triangle, and means adjustable on the

body member for engaging the heel of the boot to cooperate with the loop member in supporting the boot.

7. A boot holder comprising a wire rod formed in the shape of a triangle, the base of which is shaped downwardly and inwardly to form a loop for engaging the toe of a boot, a body member extending rearwardly of the boot from the apex of the triangle, means on the body member for engaging the heel of said boot, and resilient means engaging the heel engaging member for holding said member in engagement with the heel of said boot.

8. A boot holder comprising a wire rod formed in the shape of a triangle, the base of which is shaped downwardly and inwardly to form a loop for engaging the toe of a boot, a body member extending rearwardly of the boot from the apex of the triangle, means on the body member for engaging the heel of said boot, and means for adjusting the tension on the heel engaging means.

9. A boot holder comprising a wire rod formed substantially in the shape of a triangle, the base of which is shaped downwardly and inwardly to form a loop for engaging the toe of a boot, a body member extending rearwardly of the boot from the apex of the triangle, means on the body member for engaging the heel of said boot, means for adjusting the tension on the heel engaging means, and means engaging the boot holder adjacent the apex of the triangle for supporting same and the boot to which it is applied.

10. A boot holder comprising a wire rod formed substantially in the shape of a triangle, the base of which is shaped downwardly and inwardly to form a loop for engaging the toe of a boot, a body member extending rearwardly of the boot from the apex of the triangle, means on the body member for engaging the heel of said boot, means for adjusting the tension on the heel engaging means, and a hook member hingedly connected to the boot holder for supporting same and the boot to which it is applied, said hook member being foldable onto the boot holder when not in use.

11. A boot holder comprising a body member, means on the body member forming an opening adapted to engage over the toe of the boot, a U-shaped member, one shank of said U-shaped member being bent laterally therefrom for engaging the rearward portion of the boot, and resilient means on the body member for engaging the U-shaped member to adapt the device for various size boots.

12. A boot holder comprising a wire rod formed to provide an opening adapted to fit over the toe of the boot, a body member extending rearwardly of the boot, and a U-shaped member movable on the body member for engaging the heel of the boot to cooperate with the wire rod in supporting the boot.

13. A boot holder comprising a wire rod formed to provide an opening adapted to fit over the toe of the boot, a body member extending rearwardly of the boot, a U-shaped member movable on the body member for engaging the heel of the boot to cooperate with the wire rod in supporting the boot, and means on the body member for exerting pressure on the U-shaped member to hold same in engagement with the heel of the boot.

14. A boot holder comprising a wire rod formed to provide an opening adapted to fit over the toe of the boot, a body member extending rearwardly

of the boot, means movable on the body member for engaging the heel of the boot to cooperate with the wire rod in supporting the boot, means for adjusting the tension on the heel engaging means, and means engaging the boot holder at substantially the center thereof for supporting the same and the boot to which it is applied.

15. A boot holder comprising a wire rod formed to provide an opening adapted to fit over the toe

of the boot, a body member extending rearwardly of the boot, means movable on the body member for engaging the heel of the boot to cooperate with the wire rod in supporting the boot, means for adjusting the tension on the heel engaging means, and a hook member hingedly connected to the boot holder for supporting same and the boot to which it is applied.
